DISPLAY STAND

David E. Smith, Cincinnati, Ohio, assignor to Storrs
Schaefer, Inc., Cincinnati, Ohio, a corporation of Ohio

Filed Oct. 19, 1965, Ser. No. 87,600

Term of patent 14 years

(Cl. D80—9)

FIG. 1

FIG. 5

FIG. 4

FIG. 2

FIG. 3

FIG. 1 is a top plan view of a display stand showing my new design;

FIG. 2 is an elevational view thereof;

FIG. 3 is another elevational view thereof taken from a position sixty degrees from that of FIG. 2;

FIG. 4 is a cross-sectional view taken on line 4—4 of FIG. 2; and

FIG. 5 is a fragmentary cross sectional view taken on line 5—5 of FIG. 2, the broken line representation of displayed articles being for purposes of illustration only.

I claim:

The ornamental design for a display stand, as shown and described.
